UNITED STATES PATENT OFFICE.

EMILIO QUEROL Y DELGADO, OF BROOKLYN, NEW YORK, ASSIGNOR TO HIMSELF, JAMES WRIGHT, ELIAS DURLACH, AND MORRIS BOOKMAN, ALL OF SAME PLACE.

SEWING-MACHINE.

SPECIFICATION forming part of Letters Patent No. 377,515, dated February 7, 1888.

Application filed January 21, 1887. Serial No. 225,024. (No model.)

To all whom it may concern:

Be it known that I, EMILIO QUEROL Y DELGADO, a subject of the King of Spain, at present residing in Brooklyn, Kings county, 5 New York, have invented a new and Improved Sewing-Machine, of which the following is a full, clear, and exact description.

The object of my invention is to provide a new and improved sewing-machine adapted to 10 form one or two parallel rows of stitching.

The invention consists in the construction and arrangement of various parts and details and combinations of the same, as will be fully described hereinafter, and then pointed out in 15 the claims.

Reference is to be had to the accompanying drawings, forming a part of this specification, in which similar letters of reference indicate corresponding parts in all the figures.

20 Figure 1 is a plan view of my improvement. Fig. 2 is a bottom view of the same. Fig. 3, is a side elevation of the same, with parts in section. Fig. 4 is a sectional end elevation of the same on the line $x-x$ of Fig. 3. Fig. 5 is a 25 plan view of the shuttle-race and its contents. Fig. 6 is a vertical cross-section of the mechanism for operating the needle-bar on the line $z-z$ of Fig. 3. Fig. 7 is a sectional side elevation showing the connection of the needle-bar with 30 the needle-bar-lever, and Fig. 8 is a transverse section taken on the line $z'-z'$ of Fig. 3.

On top of the casing A is hinged the bed-plate A', supporting in suitable bearings on its under side the main shaft B, carrying the 35 usual driving-pulley, B', and the fly or hand wheel B''. The cam-wheel C is secured on the shaft B, and is provided on one face with the cam-groove C', in which operates a pin or friction-roller, D', held on the lower end of the 40 vertical bar D, having one bearing in the bed-plate A', and another bearing, E', in the arm E, which is open at the rear and on top.

The bearing E' is provided with a removable end plate or cover, E'', held on the arm E 45 by pins or other means. The upper end of the vertical bar D is provided with a socket, D', in which fits the reduced end of the horizontal needle-bar lever D³, pivoted at D⁴ to the horizontal extension of the arm E. The front 50 reduced end of the lever D³ fits into a recess

or socket, F', formed on the needle-bar F, adapted to slide vertically in suitable bearings formed on the head E³, having a removable front plate, E⁴. The take-up mechanism is located in the head E³, and consists of the 55 vertically-sliding and spring-actuated bar G' and the arms G⁵, pivoted to the enlarged part of the said bar G' and held normally in a horizontal position by the springs G⁶, the said arms being provided with eyes G⁷, through which 60 the threads pass. The tension devices H are secured to the lower end of the head E³, and each consist of a spring-bar having a half-round end, E², fitting in a correspondingly-shaped head, H², secured to the head E³. The 65 head H² is provided with a notch, H³, through which the thread passes, and the pressure of the spring-bar is regulated by the bolt and nut H⁴.

The presser-bar I is mounted to slide vertically in the said head E³, and on its upper end is pivoted the cam-lever I', acting on the top plate of the head E³, and serving, in conjunction with the spring I², to raise or lower the presser-bar I. On the lower end of the 75 presser-bar I is secured the presser-foot I³, having three prongs forming two slots for the passage of the needles F⁴.

The serrated feed-dog J, located below the presser-foot I³ and in a suitable slot formed in 80 the bed-plate A', is secured to feed-bar J', adapted to slide crosswise in a bearing formed in the middle of the partition A², held on the under side of the bed-plate A', which is also provided with a slot, A³, on each side of the 85 said partition A², forming the raceway for the shuttles. The bar J' is pivoted by means of the pin J², which passes through its forked end, and is provided with a lug, J³, against which the cam-arm J⁴ on the beveled end J⁵ of 90 the rod J⁶ engages. The rod J⁶ is mounted in bearings on the under side of the bed-plate A', and is provided with the arm J⁷, which has its free end engaging the cam-groove K' in the cam K on the shaft B, the said arm J⁷ being 95 held in contact with the groove K' by the spring J⁸. The return movement of the feed-bar J' is accomplished by the spring J⁹, and the amount of feed is regulated by the wedge L, secured to the rod L' in bearings on the un- 100

der side of the bed-plate, and provided with a pin projecting through a slot, A⁴, in said bed-plate, and provided with a button, L³.

In the partition A² is formed a transverse slot, A⁵, (see Fig. 4,) in which slides the cross-head N, supporting the shuttle-carriers O O, located one at each side of the said partition A². Each shuttle-carrier O supports a shuttle, P, of any approved construction, held in place on the said carrier by a spring-lug, O', bent upward from the said spring-carrier and fitting into a notch, P', located on top of the pointed end of the shuttle P.

The cross-head N is provided with a downwardly-projecting pin, N', which passes into the forked end of the arm Q' of the bell-crank lever Q, pivoted at Q² to the under side of the bed-plate A', and having its other arm, Q³, pivotally connected with the bar R, adapted to slide vertically in suitable bearings secured to the under side of the bed-plate A'. The sliding bar R is provided with a pin or friction-roller, R', which engages the cam-groove C², formed on the rim of the cam-wheel C.

The bobbins S and S', carrying the needle-threads T and T', are held on the bobbin-spindles S², secured to the horizontal extensions of the arm E. The threads T and T' pass from the bobbins S and S' to an eye, U, on top of the head E³, and from this eye U one thread, T, passes down on the inside of the lever E to the tension device H, and then the thread passes upward and through the eye G⁷, formed on the outer end of the take-up arm G⁵ of the take-up mechanism G. The thread T then passes downward to the eye F⁵ on the needle-bar F, and from there to the eye of the needle on the right side. The other thread, T', passes from the eye U to a second eye, U', on top of the head E³, and then downward to the tension device H² on the front plate, E⁴, of the head E³, and then up to the eye G⁷ of the other take-up arm, G⁵, and then the thread passes downward and through the eye F⁵ on the needle-bar F, from which the thread passes to the eye of the needle F⁴ on the left side.

The slots A³, forming the raceway of the shuttles, are covered by sliding plates W, in the usual manner.

The operation is as follows: A revolving motion is imparted in the usual manner to the main shaft B and its cam-wheel C, and the latter imparts, by means of the cam-groove C², the vertical arm D, and the horizontal arm D³, a vertical sliding motion to the needle-bar F, which in its descent acts on the take-up mechanism G, which is carried downward with the needle-bar F, and thus permits the lower ends of the threads T and T' to follow the needles F⁴. When the needle-bar F is on its upward stroke, then the take-up mechanism G exerts a pull on the threads T and T', which are thus unwound from their respective bobbins S and S'. The lower ends of the threads T and T' are held in the cloth to be sewed, and the tension mechanisms H H prevent a too rapid unwinding of the threads from their respective

bobbins, and also prevent breakage of the threads. The shuttle-carriers O are actuated by the rotation of the cam-wheel C, which imparts, by means of the cam-groove C² and the pin R', a sliding motion to the bar R, and the latter imparts a swinging motion to the bell-crank lever Q, which causes the cross-head N, supporting the said shuttle-carriers O, to slide forward and backward in its bearings on the partition A² of the bed-plate A'. The shuttles P each form a loop, which, in conjunction with the action of the respective needle-thread, forms a stitch in the usual manner, and as said loops are formed at the same time and two needles descend, I form two stitches simultaneously. As the formation of each stitch takes place in the usual manner, I need not describe it. The vertical arm D, acting on the horizontal lever D³, connected with the needle-bar F, can be easily disconnected and removed from the machine for repairs or for other purposes by taking off the cover E² of the bearing E' in the arm E, which then permits of disconnecting the arm D from the reduced end of the horizontal lever D³, the removal of which cover is effected by withdrawing the pin a. (See dotted lines in Fig. 1 and full lines in Fig. 8.)

One of the needles and its corresponding shuttle and thread may be dispensed with, and the sewing-machine will then operate as a single-stitch machine. The distance between the two needles and the two shuttles may be increased or diminished to suit the width of the two parallel rows of stitches to be made.

The take-up, the tension device, and the feeding devices herein shown and described form no part of this application, they being made the subject of separate applications numbered 256,885, 256,886, and 256,887, respectively.

Having thus described my invention, what I claim as new, and desire to secure by Letters Patent, is—

1. In a sewing-machine, the combination, with the needle-bar carrying two needles, of a partition having a transverse and a vertical slot, a cross-head traveling in the said transverse slot, two shuttle-carriers secured to the said cross-head, a shuttle in each of the said carriers, and a feed-dog held in the said vertical slot in the partition between the said shuttle and the said needle, and means for actuating the shuttle-carriers and feed-dog, substantially as shown and described.

2. In a sewing-machine, the bed-plate A' and the arm E, having the removable cover E', in combination with the main shaft B, journaled in bearings on the said bed-plate A', the cam-wheel C, having on one face a cam-groove C², the upright arm D, having its bearing in the said bed-plate and in the said arm E, and provided with the socket D², and the needle-bar lever D³, fitting with its reduced end in the said socket D², substantially as shown and described.

3. In a sewing-machine, the combination, with the bed-plate provided with ways on its under side, of a cross-head held to slide in the

said ways, shuttle-carriers secured to said cross-head, a sliding bar, a bell-crank lever connected to said cross-head and sliding rod, and a cam for operating the sliding rod, substantially as herein shown and described.

4. In a sewing-machine, the shuttle-carriers O, the shuttles P, supported in the said shuttle-carriers O, the cross-head N, supporting the said shuttle-carriers, and the partition A², having a slot, A⁵, in which travels the said cross-head N, in combination with the bell-

crank lever Q, connected by one arm with the said cross-head N, the sliding bar R, pivotally connected with the other arm of the bell-crank lever Q, and the cam-wheel C, secured to the main shaft B, and having the cam-groove C², in which operates the pin R' of the said sliding bar R, substantially as shown and described.

EMILIO QUEROL Y DELGADO.
